UNITED STATES PATENT OFFICE.

JOSEPH CHOCHOL AND MICHAEL DYKAS, OF CHICAGO, ILLINOIS.

AEROPLANE.

Application filed August 4, 1921, Serial No. 488,753. Renewed January 31, 1923.

To all whom it may concern:

Be it known that we, (1) JOSEPH CHOCHOL and (2) MICHAEL DYKAS, citizens of the United States of America, residing at Chicago, in the county of Cook and State of Illinois, have invented certain new and useful Improvements in Aeroplanes, of which the following is a specification.

This invention relates to certain new and useful improvements in aeroplanes and has particular reference to the provision of an improved biplane with a novel arrangement and means for driving helicopter or lifting propellers and forward propulsion propellers by means of a single engine located in the forward part of the fuselage or body.

The primary object of the invention is to utilize in a simplified and improved manner a single engine for driving a forward screw propeller for imparting forward movement to the aeroplane and one or more horizontally disposed helicopter or lifting propellers for assisting in ascension.

With the above general objects in view and others that will appear as the nature of the invention is better understood, the same consists of the novel form, combination and arrangement of parts hereinafter more fully described, shown in the accompanying drawings and claimed.

In the drawings, wherein like reference characters designate corresponding parts throughout the several views,

Figure 1 is a top plan view of a biplane constructed in accordance with the present invention partly broken away,

Figure 2 is a fragmentary top plan view of a modified form of the invention,

Figure 3 is a front elevational view of the device shown in Fig. 1,

Figure 4 is a fragmentary horizontal sectional view taken upon line IV-IV of Fig. 3,

Figure 5 is a view partly in vertical section and partly in front elevation of the device shown in Fig. 2, and

Figure 6 is a vertical sectional view taken substantially upon line VI-VI of Fig. 5.

Referring more in detail to the several views, the present invention is particularly adapted to provide forward propulsion and lifting propeller mechanism for biplanes embodying a body or fuselage 5, a rotary guiding means and tail or empennage 6 and forward superposed planes 9 and 10 which

project beyond opposite sides of the fuselage 5 at the forward end of the latter and which are suitably interbraced as at 11. The biplane is also provided with a suitable understructure 12 supporting a transverse 60 axle 13 upon which are mounted landing wheels 14 in the usual way.

The present invention contemplates the provision of a suitable motor 15 within the forward end of the fuselage 5 and having a 65 forwardly projecting shaft portion 16 on which is mounted a forward screw propeller 17 adapted to cause forward traveling movement of the aeroplane, said motor 15 also being provided with a rearwardly extending 70 shaft portion 18 with a bevel gear 19 secured thereon and operatively geared to one or more vertical shafts 20 having horizontally disposed lifting propellers 21 fixed upon the upper ends thereof. 75

In the form of the invention shown in Figs. 1, 3 and 4, a shaft 22 is journaled in a horizontal position at each side of the fuselage 5 between the planes 9 and 10 with its inner end portion journaled in the side 80 of the body and having a bevel gear 23 loosely mounted upon the same in mesh with the bevel gear 19. Each bevel gear 23 is associated with a clutch element 24 operable by a hand lever 25 for connecting or disconnecting the same from its shaft 22, and a bevel gear 26 is fixed upon the outer end of each shaft 22 in mesh with a further bevel gear 27 fixed upon a vertical shaft 20 suitably journaled in bearings 29 carried by the 90 planes 9 and 10 near their outer ends. Each shaft 20 projects upwardly through the upper plane 10 and has a lifting propeller 21 fixed thereon.

In the operation of the invention, the 95 power from the engine shaft is transmitted to the propeller 17 for causing forward movement of the aeroplane and should the operator desire to ascend, such ascension may be expedited by engaging the clutch 100 elements 24 with the bevel gears 23 so as to cause the shafts 22 to be driven, thus causing rotation of shafts 20 and lifting propellers 21. When the desired height has been reached, the clutch elements 24 may be 105 disengaged and the course of the aeroplane controlled in the usual way. The lifting propellers 21 will be found exceedingly useful in obtaining a more direct ascension with a limited amount of forward travel 110

of the aeroplane in limited space and if the same are allowed to revolve freely they will offer a resistance to the aeroplane when descending.

- 5 In the form of the invention shown in Figs. 2, 5 and 6, the engine 15 has its rearwardly projecting shaft portion 18 with the bevel gear 19 fastened thereon in mesh with a bevel gear 30 which is fixed upon 10 the lower end of a central vertical shaft 31, such shaft 31 being disposed midway between the ends of the planes 9 and 10 instead of adjacent the ends of said plane, and only a single lifting propeller 21 being 15 employed, which propeller is fixed upon the upper end of the shaft 31 above the upper plane 10. Suitable bearings for the vertical shaft 31 are provided as at 32 in the plane 10 and fuselage 5 and a clutch element 33 is provided upon the shaft 31 so as 20 to engage or disengage the bevel gear 30 from the shaft 31, such clutch element 33 being actuated by the hand lever 34. The operation of the form of the invention 25 shown in Figs. 2, 5 and 6 is substantially the same as that described in connection with the other form except that only a single lifting propeller is provided and a single controlling lever necessary.
- 30 From the foregoing description it is believed that the construction and operation as well as the advantages of the present invention will be readily understood and appreciated by those skilled in the art.
- 35 Minor changes may be made in the inven-

tion without departing from the spirit and scope thereof as claimed.

What is claimed as new is:—

In combination with a fuselage having superposed planes at the forward end thereof and extending from opposite sides of the same, an engine in the forward end of said fuselage having rearwardly and forwardly extending shaft portions, a screw propeller for causing forward movement of the aero- 40 plane fixed upon the forwardly projecting portion of the engine shaft, a bevel gear fixed upon the rearwardly extending portion of the engine shaft, a transverse shaft arranged in a horizontal position at each 45 side of the fuselage and terminating adjacent the outer ends of the planes between the latter, bevel gears slidably keyed upon the inner ends of said last named shafts 50 adapted to mesh with the first named bevel gear, manually operable means to connect or disconnect either one or both of the last named bevel gears from said first named bevel gear and including a pair of horizontal rearwardly extending levers arranged 55 within the fuselage rearwardly of the engine, vertical shafts journaled near the outer ends of the planes and rotatably geared to the outer ends of said last named shafts, and lifting propellers fixed upon the upper 60 ends of the vertical shafts above said plane.

In testimony whereof we affix our signatures.

JOSEPH CHOCHOL.
MICHAEL DYKAS.
